UNITED STATES PATENT OFFICE.

THOMAS BREEN, OF KNOWLTON, PENNSYLVANIA.

RAILROAD-FROG.

SPECIFICATION forming part of Letters Patent No. 253,177, dated February 7, 1882.

Application filed October 15, 1881. (No model.)

To all whom it may concern:

Be it known that I, THOMAS BREEN, a citizen of the United States, residing at Knowlton, in the county of Delaware and State of Pennsylvania, have invented certain new and useful Improvements in Railroad-Frogs, of which the following is a specification, reference being had therein to the accompanying drawings, and in which—

10 Figure 1 is a plan view of my improved automatic frog. Fig. 2 is a section taken inside of the guard, showing in side view the frog-actuating lever. Fig. 3 is a section through the shifting rail and its bed, showing the pivotal pin and guide-pin of said rail. Fig. 4 is a vertical section, drawn through the frog-operating mechanism. Fig. 5 is a horizontal section, showing in plan the aforesaid mechanism; and Fig. 6 is a detailed side view of the guard 15 and lever, showing the bolt serving as its fulcrum and the bolt or pivot locking plate, also adapted to close the opening in the guard through which the spring-rod of the frog or shifting rail passes.

20 This invention relates to improvements in that class of devices termed "automatic frogs;" and it consists in the substitution, in lieu of the common frog, of a section of ordinary T-rail, one end disposed at the confluence of the 25 inner rails of a side and main track, and the other end adapted to be shifted from one to the other of the diverging sections of the said inner rails of the two tracks; secondly, of mechanism for effecting the automatic adjustment or shifting of the frog-rail, and in details 30 of construction, substantially as hereinafter more fully set forth and claimed.

Referring to the accompanying drawings, A is a section of ordinary T-rail, one end being 40 disposed at the convergent ends of the inner rails of a side and a main track, A' A², and the other end capable of being shifted from one to the other of the divergent ends of the said inner rails of the two tracks. The shifting rail A, which takes the place of the usual frog heretofore employed, is limited in its movement, in line with either one or the other of the inner rails, as it is shifted by the passing 45 of the train of cars, either from one side to the other of the main track, by means of curved or bent-over bolts a, screwed into the bed-casting B, upon which the shifting rail moves. Like

means are used to secure the rails of the tracks A' A² in position. The rails A' and A² are connected by the plate b, having a drain-opening, b', through it, the connection being at their ends partly where they abut the smaller or more adjustable end of rail-section A, and this connecting-plate additionally strengthens and secures them in position. The shifting rail or frog A is pivoted in the bed B, having a countersunk socket or opening, c, by means of a pin or pivot, c', fitting in said socket or opening, and having at its point of connection with the rail a rounded or convex shoulder, c², seated in the countersink of the aforesaid socket. The shoulder re-enforces or strengthens the pivot to prevent liability of breaking off, especially when the shifting rail is exposed to friction or lateral thrust by the impingement of the flanges of the wheels of a passing train. From the same side of the rail A depends a second pin or stud, d, which works in and passes through and below a transverse slightly-curved slot, e, in the bed B, as seen in Figs. 3 and 4.

C is a rod sliding in a passage in the bed B, as seen in Figs. 4 and 5, and exposed to the action of a spring, C', preferably encircling it. The inner end of this rod has an aperture 80 which receives the pin or stud d of the rail A, which is connected to the rod by a removable pin, f, inserted into an aperture in the end of the rod and through an aperture in the stud d, as clearly seen in Figs. 4 and 5. The opposite 85 end of the rod C receives and permits of the screwing into it of a bevel-faced bar, C², therefore readily detachable or removable, and which extends just outside of one of the side-track rails, as seen in Figs. 4 and 5.

D is a lever centrally supported by rods g, one arranged upon each side of its center, encircled by springs g', and adapted to move up and down in apertures g² in one of the flanges of one of the outer rails to enable the lever to stand just above the beveled face of the frog-actuating bar C², as seen in Figs. 2 and 4. In practice bar D will be so lengthened as to admit the full action of the shifting rail A before the flange of the wheel has reached it, and such construction will necessitate auxiliary springs similar to springs g', which will be located near the terminal point of bar D.

In the center of the lever D is a vertical

slot, *h*, through which passes its pivotal bolt *h'*, (see Figs. 2 and 4,) inserted through the guard *E*, affixed to the rail flange or foot, and screwed into the web of the rail and an intermediate plate, if desired. While the springs *g* hold the lower beveled point, *i*, of the lever *D* out of forcible contact with the bar *C²* the slot *h* permits of the depression of the lever by the action of the car-wheels when it is desired to bring the lever into forcible contact with the aforesaid bar for shifting the rail or frog *A*.

Fitted upon the pivotal bolt *h'* of the lever *D* is a plate, *j*, with its edges bent so as to embrace the head of the bolt, and extended down so as to cover the entrance of the sliding rod and bar passage to exclude water and dirt therefrom. Its lower end has a tooth or stud, *k*, on its inside to enter an aperture, *k'*, in the guard *E*.

It will be noticed that when the pivotal bolt is screwed home the upper end of the plate *j* is slipped upon the head thereof, and its lower portion sprung over the entrance of the sliding rod and bar passage, its tooth entering the aperture *k'*, thus effecting the simultaneous locking of the bolt or pivot against being jarred loose by the motion of the cars, with the closing of said passage for the purpose above stated. As the wheel of the engine or car passes upon the end of the lever *D* next to it, and approaches the pivotal point of the lever, the shifting of the frog-rail *A* will be commenced and be completed when the wheel reaches the pivotal point of the lever, and thus allow the car or train to cross the main track. After the passage of the cars or train the spring upon the rod *C* will automatically spring or return the frog-rail *A* in line with the inner rail of the main track, and thus keep the main track always unbroken.

I claim and desire to secure by Letters Patent—

1. In an automatic railway-frog, the combination, with the frog-rail *A*, of the pivotal pin 45 having a rounded reinforcing shoulder fitted in a countersunk aperture in the bed or casting, substantially as and for the purpose set forth.

2. In an automatic railway-frog, the combination, with the shifting rail *A*, of the spring-actuated rod *C* and its beveled bar *C²*, and means for imparting a sliding motion thereto by the action of the car or train wheels, substantially as and for the purpose set forth. 55

3. In an automatic frog, the combination, with the shifting rail *A*, having connected thereto a spring-actuated rod, *C*, provided with a beveled bar, *C²*, of the lever *D*, having a beveled point and supported upon elastic 60 bearings, substantially as and for the purpose set forth.

4. In an automatic frog, the combination, with the headed pivotal bolt of the lever *D*, of the plate *j*, adapted to embrace the head of the bolt, and to be sprung over and cover the entrance of the sliding-bolt passage, as set forth, substantially as and for the purpose specified. 65

5. In an automatic railway-frog, the combination, with the frog-operating rod and bar *C²*, having the beveled face, of the lever *D*, having the beveled point, and the vertical slot through which its pivot passes, and supported in an elevated position out of forcible contact 75 with the aforesaid bar upon springs encircling rods having vertical movement, substantially as and for the purpose specified.

In testimony whereof I affix my signature in presence of two witnesses.

THOMAS BREEN.
